UNITED STATES PATENT OFFICE.

HARRY D. LATHROP, OF CHICAGO, ILLINOIS.

BOTTLE-WASHING MACHINE.

Application filed March 10, 1921. Serial No. 451,134.

To all whom it may concern:

Be it known that I, HARRY D. LATHROP, a citizen of the United States, and a resident of the city of Chicago, county of Cook, and 5 State of Illinois, have invented certain new and useful Improvements in Bottle-Washing Machines, of which the following is a specification.

My invention relates to improvements in 10 bottle washing machines, and has for its object an improved construction of this character which is simple, capable of economical manufacture and highly efficient in use.

Other objects will appear hereinafter.

15 The invention consists in the combinations and arrangements of parts hereinafter described and claimed.

The invention will be best understood by reference to the accompanying drawings 20 forming a part of this specification, and in which,

Fig. 1 is a partial top plan view of a machine embodying the invention;

Fig. 2, a transverse section taken on line 5 2—2 of Fig. 1; and

Fig. 3, an enlarged detail section of a spraying device employed in the machine.

The preferred form of construction as 10 illustrated in the drawings comprises a suitable tank 4 adapted and arranged to contain the hot washing fluid or compound. A suitable track or guide-way is extended longitudinally along the top of tank 4 and consists of two angle irons 5 arranged as shown. A spray head 6 is arranged adjacent one end of tank 4 under the guides 5, said spray head being provided in its top with a plurality of spray openings 7 arranged and adapted to project jets of water upwardly into the mouths of milk bottles or the like arranged in inverted position in a suitable crate 8 traveling on said guides, as indicated by dotted lines in Fig. 2. The spray head 6 is supplied with water through a pipe 9 leading to a coil 10 located in tank 4 and supplied with cold water under pressure through a branch pipe 11 leading from a cold water supply pipe 12 as shown. By this arrangement, the cold water passing from the coil 10 will be moderately heated before being projected into the bottles to be washed, thus serving as a preliminary rinse for said bottles and also serving to moderately heat the same to prevent breaking thereof upon subjection to more in-

tense heat. Thus the rinsing water is not only moderately heated by this arrangement but the hot solution in tank 4 is somewhat cooled thereby, thus tending to temper the temperature of the washing solution in tank 4 and prevent undue heating thereof. The preliminary heating of the water passing to the spray head 6 also has a tendency to increase the pressure thereof.

A washing spray head 13 similar in all respects to the spray head 6 is located under the guides 5 and over one end of the tank 4 so that a solution spraying thereon will drain back into said tank. The spray head 13 is supplied with washing fluid by means of a pipe 14 leading from a perforated casing 15 located in the bottom of tank 4. The casing 15 is supplied with steam through a steam nozzle 16 connecting with a branch pipe 17 leading from steam supply pipe 18 and whereby a jet of steam will be supplied to said casing. A cold water supply pipe 19 leads into the casing 15 adjacent the end of nozzle 16 and co-operates therewith and with the incoming steam to forcibly eject 80 the washing compound through pipe 14 and spray head 13, said washing compound being projected upwardly into the inverted mouths of the open bottles as they pass over spray head 13. Another spraying device 20 is located in the bottom of tank 4 and similar 85 in all respects to the spraying device 15, being supplied with steam through a branch 21 leading from steam supply pipe 18 and with cold water through a branch 22 lead- 90 ing from cold water supply pipe 12.

A pipe 23 leads from the spray casing 20 to a spray head or pipe 24 located above the guides 5 and above the crates of bottles 8 passing through the machine. By this arrangement, sprays of hot washing fluid will be forced from the tank 4 into and over the bottles in crate 8 as they pass through the machine, the inverted bottom of crate 8 being made of wire mesh material for the purpose.

By this arrangement, a simple and effective bottle washing machine is provided which is capable of economical manufacture.

While I have illustrated and described the 105 preferred form of construction for carrying my invention into effect, this is capable of variation and modification without departing from the spirit of the invention. I, therefore, do not wish to be limited to the precise 110

details of the construction set forth, but desire to avail myself of such variations and modifications as come within the scope of the appended claims.

5 Having described my invention, what I claim as new and desire to secure by Letters Patent is:

1. A washing machine comprising a tank containing hot washing fluid; washing means associated with and using fluid from said tank; rinsing means associated with said tank and arranged to rinse an article prior to subjection to said washing means; and a supply pipe for said rinsing means passing through said tank, substantially as described.

2. A washing machine comprising a tank; a washing spray located above said tank; rinsing means positioned adjacent one end of said tank but not over the same and arranged to rinse articles prior to subjection to said washing spray; and a supply pipe for said rinsing means passing through said tank, substantially as described.

3. A washing machine comprising a tank containing hot washing fluid; washing means associated with and using fluid from said tank; rinsing means associated with said tank and arranged to rinse an article prior to subjection to said washing means; a pipe coil in said tank; a cold water supply pipe leading to said coil; and a supply

pipe leading from said coil to said rinsing means, substantially as described.

4. A washing machine comprising a tank; a washing spray located above said tank; rinsing means positioned adjacent one end of said tank but not over the same and arranged to rinse articles prior to subjection to said washing spray; a pipe coiled in said tank; a cold water supply pipe leading to said coil; and a supply pipe leading from said coil to said rinsing spray, substantially as described.

5. A washing machine comprising a tank; a guide passing over said tank; a washing spray located over said tank and under said guide; a rinsing spray located under said guide and not over said tank and arranged to rinse articles on said guide prior to subjection to said washing spray; a coil located in said tank; a cold water supply pipe leading to said coil; a supply pipe connecting said coil with said rinsing spray; and means for forcing fluid from said tank to said washing spray, substantially as described.

In testimony whereof I have signed my name to this specification in the presence of two subscribing witnesses.

HARRY D. LATHROP.
